CLAIM

The ornamental design for a key, as shown and described.

DESCRIPTION

Fig. 1.1 is a perspective view of a key according to my new design;

Fig. 1.2 is a front view thereof;

Fig. 1.3 is a rear view thereof;

Fig. 1.4 is a top plan view thereof;

Fig. 1.5 is a bottom plan view thereof;

Fig. 1.6 is a left side view thereof; and

Fig. 1.7 is a right side view thereof.

The broken lines show portions of the key that form no part of the claimed design.
